UNITED STATES PATENT OFFICE

CHARLES W. HARGRAVES, OF YEOMAN, INDIANA

COMBINATION HOG OILER AND FEEDER

Application filed December 26, 1928. Serial No. 328,579.

This invention relates to a novel compound structural assembly having the double function of providing novel hog oilers, and a complementary feeder.

- 5 The gist of the invention resides in the provision of a compact and convenient structural assembly involving the use of a feed container provided with internal agitating elements carried by suspension means, also 10 functioning to carry and intermittently cooperate with two or more hog oilers, whereby the rubbing action of the hogs against said oilers will permit them to develop energy for actuating the feed agitator.

- 15 The particular structural details employed for accomplishing this novel result will become more readily apparent from the following description and drawings.

In the drawings:

- 20 Figure 1 is a side view of the complete structure with a portion broken away and in section,

Figure 2 is a top plan view of the same, Figure 3 is an enlarged vertical sectional

- 25 or transverse view through the feeder,

Figure 4 is a detail view of one of the movably mounted hog oilers,

Figure 5 is a cross section through the oiler seen in Figure 4,

- 30 Figure 6 is a sectional view taken approximately upon the plane of the line 6—6 of Figure 1.

In carrying out the invention, I provide a feeder comprising a container generally designated by the reference character 7 which may be an ordinary box with removable cover having a discharge slot 8 at its bottom and inclined false bottom wall 9 cooperating therewith to facilitate discharge under the 40 action of gravity.

Extending through and beyond the opposite end of this box is a horizontal suspension pipe 10 carrying a plurality of longitudinally spaced depending agitating bars 45 11. These are attached to the pipe through

the medium of the tension bracket 12 and the lower end thereof extends downwardly through and beyond the discharge slot 8. These agitators are adapted to have a slight transverse swinging motion and a relatively great longitudinal sliding motion, whereby when they are thus moved, the feed will be agitated to prevent clogging at the discharge 8.

A receptacle or trough may be located intermediate the discharge for convenient feeding cooperable with the extending end of the extension pipe 10 are the hog oilers generally designated by the reference characters 13 each oiler is substantially the same in construction and by referring to Figure 4 it will be seen that each comprises a core or body member 14 provided with radial discharge ducts 15 for the oil.

Embedded in this body is a delivery pipe 16 having orifices in registry with the passages 15. Attached to the surface of the body is a layer of absorbent material 17 having desirable capillary property to provide for uniform distribution of the oil. The pipe 16 is attached by a union 18 to the suspension pipe 10. At each end of the feed box and disposed in parallelism above the extension pipe is a horizontal guide loop 19.

As shown in Figure 4, a short length of 75 pipe 20 is also connected with the union 18 and it extends up through the loop 19 where it is provided at its upper end with a rocker head 21 thus allowing the hog oiler to rock slightly back and forth and to slide longitudinally in the loop 19.

The feed pipe 22 will feed the source of supply to any appropriate location and the supply may be under pressure or by gravity, as is desired.

With this arrangement it will be seen that the continual and natural rubbing action of the animal against the oilers 13 will cause them to rock as well as to slide, then, the agitators are supported on the same device in 85 90

which the oilers are connected, sufficient energy will be supplied to actuate the agitators 11 in a swinging and sliding manner to loosen the feed and to facilitate its discharge through the slot 8.

5 It is believed that by considering the description in connection with the drawing a clear understanding of the construction, advantages of the invention will be obtained 10 and therefore, a more lengthy description is regarded unnecessary.

Minor changes in shape, size and arrangement of details coming within the field of invention claimed may be resorted to in actual 15 practice if desired.

Having thus described my invention, what I claim as new is:

1. In a structure of the class described, in combination, a feed container, a plurality of 20 agitating elements supported therein, and a hog oiling device having operating connection in said agitator.

2. In a structure of the class described, in combination, a feed container having a discharge slot, a horizontal suspension member 25 supported in said container, a plurality of agitating elements carried by said elements and depending down through said discharge slot, and a hog oiling device supported on said 30 element and located exteriorly of the container, whereby it is permitted to be moved under the action of rubbing animals, in order to actuate said agitator.

3. In a structure of the class described, in combination, a feed box having a discharge 35 slot in its bottom, a horizontal pipe extending through bearings in the opposite end of said box above said slot, a plurality of agitating bars fastened to the interior portion of said 40 pipe and depending down through and beyond said discharge slot, and a pair of hog oiling devices supported from the opposite extending end portions of said pipe.

4. In a structure of the class described, in combination, a feed box having a discharge slot in its bottom, a horizontal oil delivering 45 and shaft forming pipe mounted in bearings, the opposite ends of said box disposed above said slot, and extending through and beyond 50 the ends of said box, agitating elements carried by said pipe and extending down through said discharge slot, a pair of hog oiling devices attached to the extending opposite ends of said pipe and each including a branch delivery pipe in communication with said first 55 named pipe, surrounding the body having discharge passages, and an absorbent covering.

5. In a structure of the class described, in combination, a feed box having a discharge slot in its bottom, a horizontal oil delivering 60 and shaft forming pipe mounted in bearings, the opposite ends of said box disposed above said slot, and extending through and beyond 65 the ends of said box, agitating elements car-

ried by said pipe and extending down through said discharge slot, a pair of hog oiling devices attached to the extending opposite ends of said pipe and each including a branch delivery pipe in communication with said first 70 named pipe, surrounding the body having discharge passages, and an absorbent covering, together with a pair of horizontally disposed loops attached to the opposite end of the end walls of said box disposed in spaced 75 parallelism above the extending end portion of said pipe, each of said hog oiling devices being forked at its upper end with a rocker edge having slideable and rocking connection with said loops.

In testimony whereof I affix my signature.
CHARLES W. HARGRAVES.
